DUST TIGHT CASING FOR CLEANING
DUST MOPS

Bertha B. Smith, South Orange, N. J.

Application May 11, 1948, Serial No. 26,310

9 Claims. (Cl. 15—89)

1

This invention relates to dust mop cleaners for household use.

The common practice of shaking a dust-laden mop out of a window, to remove the accumulated dust, is not only highly objectionable in thickly populated areas but is a violation of the sanitary code of many cities, towns and other large settlements.

To avoid the necessity of resorting to such practice, the present invention is designed to enable a dust mop to be conveniently and thoroughly cleaned indoors and the dust confined against escape and collected in a portable receptacle for disposal from time to time, as occasion may require.

An embodiment of the invention at present preferred, is illustrated in the accompanying drawings, but it is to be understood that no limitations are intended by this showing other than are imposed by the appended claims.

In the drawings—

Fig. 1 is a view in front elevation, partly in section, of the cleaner.

Fig. 2 is a side elevation, partly in section, thereof.

Fig. 3 is a detail view on an enlarged scale showing the cam-action catch employed.

Fig. 4 is a partial sectional view on the line s^4, s^4 of Fig. 3, and

Fig. 5 is a detail view of a modified form of my invention.

Referring now to the drawings, 3 indicates an outer casing or body of suitable size, form and material forming a lower portion 1 coacting with an upper portion 2 which is separable from and hinged to the body 3, as indicated at 2^a, to serve as a top closure or cover for the casing. The upper portion 2 constitutes a chambered top portion across which a yielding sidewall formed by resilient bands 14 extends, as will be pointed out hereinafter in more detail.

When the cover is swung upward on its hinged supports, it opens the casing for the entrance therein of the dust-laden end of a mop 4 and also gives access to the interior. The hinges 2^a are preferably of a conventional form that limits the opening movement of the cover and yieldingly holds it in open position.

A central opening 5 is formed in the meeting edges of the cover 2 and body 3 of the casing, through which the handle 4^a projects when a mop is entered in the casing. The diameter of the opening is made large enough to accommodate all standard mop handles.

In the upper portion of the body 3 of the casing, a beater 6 of skeleton cylindrical form is rotatably mounted in engaging relation to the mop head therein. Bearings for the cylindrical beater are indicated at 6^a and a shaft 7, projecting through an opening in the casing, terminates in a hand crank 8, for rotating the beater.

2

While any suitable form of beater may be used, the construction shown is preferred, which consists of end disks 9, 9, connected by heavy gauge wires or rods 10 secured, equally spaced about the periphery of the disks. The wires or rods 10 serve as the beater elements and may be given the undulating form shown or any other form that may be preferred.

Arranged as described, rotation of the beater causes the mop head to be successively engaged by the beater elements with sufficient force to detach the accumulated dust particles, which float about within the casing for a time and gradually settle downward.

Within the casing below the beater, a hopper-like formation 11 is provided, that extends from the side walls of the casing, inclining downward to a central discharge opening 12. The converging walls of the hopper are sufficiently inclined to prevent deposit and accumulation of dust particles thereon and are of material aid in directing movement of the dust toward the central discharge opening.

At or near the bottom of the casing, there is a portable receptacle 13, in which the dust delivered by the hopper, is deposited. The receptacle is in the form of a drawer, which is removable from the casing for conveniently disposing of the accumulated dust.

In order to hold the mop head against excessive vibration or up and down movement, under the action of the beater, it is yieldingly held, when the upper portion cover 2 is closed, pressed down in engagement with the beater, by spaced apart bands of rubber 14, or spiral springs 14^a, stretched across from side to side within the cover.

The mop handle is also yieldingly held against such movement by being clamped between upper and lower members 15 and 16 of a supporting means. The lower member 16 is rigid, unyielding and in the form of two parts 17 and 18, secured to the body of the casing in spaced apart relation, to provide a broad support for the handle and mop. The part 17 is riveted or otherwise secured to the wall of the casing, exteriorly thereof and the part 18 is bracketed to the wall within the casing. They are each provided with an upwardly opening V-shaped notch 19, proportioned to receive any standard diameter of mop handle and hold it centered relative to the opening 5 in the meeting edges of the cover and body of the casing.

The upper member 15 of the handle-supporting means is in the form of a block of compressible material, preferably rubber, which is secured to the cover within the casing and positioned to engage the mop handle between the points of support provided by the parts 17 and 18 of the lower member.

The closing of the cover is utilized and serves to move the upper member 15 of the support-

ing means, that is, the block of rubber, into engaging relation with the mop handle and to compress the rubber sufficiently to hold the handle firmly in the V-shaped notches of the lower parts of the supporting means.

In order to obtain sufficient compression of the rubber block to firmly hold mop handles of comparatively small diameter against unnecessary movement, the block is given such thickness that normally, or when a mop is not present in the casing, the block extends downward substantially to the full depth of the notches in the parts 17 and 18 of the lower member of the support, thus assuring ample compression of the block regardless of the diameter of the handle of the mop entered in the casing.

To prevent the cover from being forced open by the reaction of the compressed block of rubber, the cover is secured closed by a cam-action catch 20, pivoted at 21, to the cover and movable about the pivot, by means of a handle 22, to engage a headed stud 23, projecting from a plate riveted or otherwise secured to the body of the casing. The curvature of the free end 24 of the catch is such that its frictional hold on the stud is increased as the catch is given increased movement, clockwise, about its pivot, to hold the cover down in tightly closed relation on the body of the casing.

As the construction, operation and many important advantages of the invention will be apparent from the foregoing, it is not deemed necessary to further describe the same.

I claim:

1. A dust mop cleaner, comprising a casing normally closed against the escape of dust, the casing being divided horizontally to provide a chambered top portion and a body portion, said top portion being hinged on one side to the body portion to give access to the interior for the entrance and removal of the head end of a mop, a rotatable beater mounted in the body of the casing in engaging relation to a mop head entered therein, a wall opening formed at the division line between the body and the free side of the hinged top of the casing of a size for accommodating mop handles, fixed non-yielding supports secured inside and outside the front wall of the body portion of casing at the aforesaid line of division and spaced apart to support a mop handle horizontally when the handle is inserted in said casing with the head contacting the beater, and yieldable means within the inside of the front of the chambered top and actuated by the same when closed to exert pressure on the dust mop handle to hold the same firmly against movement in the supports during the cleaning operation.

2. A dust mop cleaner, as defined in claim 1, in which the yieldable means within the chambered top engages and exerts pressure on the upper side of the mop handle at a point intermediate its spaced apart supports.

3. A dust mop cleaner, as defined in claim 1, in which the yieldable means within the chambered top is in the form of a block of compressible resilient material suitably shaped to engage the upper side of the mop handle at a point intermediate its spaced apart supports.

4. A dust mop cleaner, as defined in claim 1, in which the yieldable means within the chambered top is in the form of a block of compressible resilient material suitably shaped to engage the upper side of the mop handle at a point

intermediate its spaced apart supports and a cam catch for drawing the top portion downward to close the same against the body portion of the casing and compress the material of said block.

5. A dust mop cleaner, comprising a casing normally closed against the escape of dust, the casing being divided horizontally to provide a chambered top portion and a body portion, said top portion being hinged on one side of the body portion to give access to the interior for the entrance and removal of the head end of a mop, a rotatable beater mounted in the body of the casing in engaging relation to the mop head inserted therein, a wall opening formed at the division line between the body and the free side of the hinged top of the casing of suitable size to accommodate mop handles, fixed non-yielding supports secured inside and outside the casing to the body thereof at the aforesaid line of division at the front of the casing and suitably spaced apart to support a mop handle horizontally when the handle is inserted in said casing with the head contacting the beater, and yieldable means within the chambered top portion extending laterally thereof and engaging and exerting pressure on the mop head to maintain it in engagement with the rotating beater.

6. A dust mop cleaner, as defined in claim 5, in which the yieldable means for engaging and exerting pressure on the mop head is in the form of a number of resilient elements that extend across the inside of the interior of the chambered top and are positioned to engage and yieldingly maintain the mop head in engagement with the beater when the top portion of said casing is closed against the body portion of said casing.

7. A dust tight casing for cleaning dust mops comprising a casing having a hinged top formed by the upper portion thereof giving access to the interior for the entrance and removal of the head portion of a mop, the said hinged top being chambered at its front to enclose the end of the mop handle and the mop head which projects into the same when the top is closed, a yieldable block carried by the inside of said hinged top at the front thereof, means secured to the casing and coacting with said yieldable block for holding the handle of the mop against movement during the cleaning of the mop head, a rotatable beater mounted within the casing in engaging relation to the mop head, the said beater being of skeleton form to permit free passage of dust through the same, a removable drawer-like receptacle at the bottom of the casing for receiving the dust particles and a hopper interposed between the beater and the receptacle for guiding and delivering the dust particles to the receptacle.

8. A dust mop cleaner, as defined in claim 7, in which the hinged top and the casing are arranged to be brought together in clamped relation about the mop handle by the closing movement of the aforesaid hinged top and a cam-action catch for locking said top in closed relation to the casing to maintain the clamping relation of the hinged top and the casing about the mop handle.

9. A dust mop cleaner, comprising a casing having upper and lower portions closed against the escape of dust, the upper portion of the casing being hinged to the lower portion of the body thereof to open the casing for entrance

therein of the dust-laden mop head of a mop handle, securing means for the mop handle comprising lower and upper parts, the lower part of the securing means being attached to the body of the casing and consisting of spaced apart members each having an upwardly opening notch therein to receive the mop handle, the upper part of the securing means being in the form of a block of yielding material carried by the hinged upper portion of the casing and compressible by the closing movement thereof to clamp the mop handle between the upper and lower parts of the securing means and a rotatable beater mounted within the lower portion of said casing in engaging relation to the mop head.
